UNITED STATES PATENT OFFICE.

WILLIAM T. HANNA, OF CINCINNATI, OHIO, ASSIGNOR, BY MESNE ASSIGNMENTS, TO THE MECHANICAL CONSTRUCTION COMPANY, OF CINCINNATI, OHIO, A CORPORATION OF OHIO.

MECHANICAL STOKER.

1,203,871.

Specification of Letters Patent. Patented Nov. 7, 1916.

Application filed January 2, 1912. Serial No. 669,057.

To all whom it may concern:

Be it known that I, WILLIAM T. HANNA, a citizen of the United States, residing at Cincinnati, in the county of Hamilton and State of Ohio, have invented certain new and useful Improvements in Mechanical Stokers, of which the following is a specification.

My invention relates to that class of mechanical stokers in which the fuel is automatically fed through the usual fuel-door opening, and is designed more particularly for use in locomotive stokers. In this class of stokers it is sometimes necessary to clear the fuel-door opening of the obstructions, due to the mechanical stoker, for hand stoking or other purposes. This generally involves more or less dismantling of the mechanical stoker with consequent loss of time and needless access of cold air to the fire box.

The object of my invention is to provide a method of mounting the stoker feed-conduit which permits easy and instantaneous clearance of the fuel-door opening and permits easy and instantaneous replacement of the stoker parts in their working position, and my invention consists in the parts and combination and arrangement of parts hereinafter described and claimed.

In the drawings, Figure 1, is a rear elevation showing my improvement in connection with a locomotive stoker with the parts in position for automatic stoking; Fig. 2, a like view showing the position of the parts when arranged for hand stoking, the ordinary fuel door being shown in the closed position and Fig. 3 an end elevation from the left of Fig. 1.

The reference numeral 1 indicates the rear end of a locomotive furnace; 2, the ordinary fuel door; 3, a hopper through which fuel may be fed to a conveyer adapted to force fuel into a feed conduit; 4, the wall of the conveyer; 5, the conveyer shaft; 6, the feed conduit leading from the conveyer to the fuel opening, and 7, a hood plate fixed to

the delivery end of the conduit, having an opening 8 through which fuel may pass from the feed conduit but otherwise closing, except for admission of fuel from the conduit. The conduit is of elbow shape, and its receiving end is provided with an annular flange 9 encircling a corresponding shoulder 10 upon the delivery end of the conveyer. Upon its elbow portion the conduit is provided with a socket boss 11 adapted to receive, and rotate upon the end of, a stud axle 12 mounted upon the frame in the same axial line with the previously mentioned flange and shoulder joint. The stud axle may be secured against longitudinal movement by a clamp 13 and set screw 14. 15 indicates a ridged shaped plate mounted upon the hood plate and adapted to deflect fuel fed therethrough. By loosening the set screw 14 the stud axle may be moved longitudinally for the purpose of mounting or dismantling the conduit. It will be noted that the conduit is pivoted or swiveled upon the annular shoulder 10 and stud axle 12 and is free to swing thereon. As the hood plate, which closes the door plate, is fixed to the conduit, by swinging the latter rearward and downward the fuel opening may be entirely cleared for hand stoking or other purposes.

I claim as my invention:

In a mechanical stoker, the combination with a furnace having a fuel opening, of a hopper located to one side of said opening, a door for said opening hinged at the opposite side wall, a fuel conduit extending from said hopper beneath said door and carrying a hood adapted to extend up to and to close said fuel opening, said conduit being rotatably supported upon a bearing at the delivery end of the hopper and upon an axle concentric with said delivery end to expose or connect with said fuel opening.

WILLIAM T. HANNA.
